UNITED STATES PATENT OFFICE

LOUIS STEINBERGER, OF NEW YORK, N. Y.

INSULATOR FOR HIGH-TENSION CURRENTS.

No. 879,068.

Specification of Letters Patent.

Patented Feb. 11, 1908.

Application filed August 12, 1907. Serial No. 388,175.

To all whom it may concern:

Be it known that I, LOUIS STEINBERGER, a citizen of the United States, and a resident of the city of New York, borough of Brooklyn, in the county of Kings and State of New York, have invented a new and Improved Insulator for High-Tension Currents, of which the following is a full, clear, and exact description.

10 My invention relates to insulators and admits of general use but is of peculiar service upon transmission lines carrying currents of very high potential, and is especially adapted to prevent arcing from the line to the support under conditions where such arcing would otherwise take place.

Among the several objects of my invention are the following:

I. To secure the greatest possible dielectric efficiency combined with a maximum of mechanical strength and a minimum of materials and weight;

II. To provide an insulator having a hood adapted to support a plurality of conductors simultaneously;

III. To provide an insulator having a hood provided with a plurality of separate channels extending in the general direction of the line;

30 IV. To provide for sheltering the entire upper portion of the insulator;

V. To provide a shield or umbrella for an insulator of such form as to direct the flow of moisture from its surface, away from the conductor;

VI. To provide an insulator having a channel, and revoluble locking members disposed within said channel;

VII. To provide a locking mechanism for the conductor of very simple form and construction possessing the highest efficiency and absolute reliability in action;

VIII. To facilitate the dripping of moisture from certain portions of the insulator by causing the moisture to be discharged therefrom in a number of separate streams;

45 IX. To facilitate the mounting, the removal and the replacement of the conducting wire or cable relatively to the insulator body;

X. To center the conducting wire or cable relatively to certain other parts;

XI. To provide various details of construction for the purpose of improving the 50 general efficiency of the insulator;

XII. To prevent undue chafing or wearing

of that part of the insulator upon which the cable or other conducting member rests;

XIII. To provide an improved form of mechanism for securely supporting and locking the cable or other conducting member relatively to the insulator body;

XIV. To prevent the formation of arcs by lengthening the path through which the arc might otherwise tend to occur;

XV. To provide means for employing insulators of comparatively small size for carrying currents of very high potential; and

XVI. To provide means for securely supporting a conductor in a manner so as to 70 make each span an independent mechanical unit.

Reference is to be had to the accompanying drawings forming a part of this specification, in which similar characters of reference 75 indicate corresponding parts in all the figures.

Figure 1 is a plan view of my improved insulator showing the mountings for the wiring or cable, the sheltering hood being removed; 80 Fig. 2 is a longitudinal central section through the insulator and its accompanying parts, showing the sheltering hood in position and also showing how the wire is mounted and held in position; Fig. 3 is a vertical 85 central cross section through the insulator and its accompanying parts, this section being taken upon a plane crossing the general direction of the wire or cable, and showing also some auxiliary wires as being supported 90 by the insulating hood; Fig. 4 is a perspective showing a tubular head through which the conducting wire or cable passes centrally, this head being provided with a divided stem for supporting the sheltering hood; 95 Fig. 5 is a perspective showing one of the clamps used for centering the main wire or cable; and Fig. 6 is a reduced plan view of the sheltering hood.

A cross arm is shown at 7 and a pin body 100 at 8. This pin body is provided with a shank 9 extending through the cross arm and is further provided with petticoats 10 and with a frusto-conical portion 11. The pin body is further provided with a threaded 105 stem 12. The insulator body is shown at 13 and is provided with a frusto-conical portion 14, the latter being provided internally with petticoats 15 integral therewith. The body portion 13 fits upon the threaded stem 12. 110

A hood 16 of insulating material is provided upon its upper surface with longitu-

dinal ribs 17 of substantially arcuate form, each rib being parallel with the general direction of the wire and extending from edge to edge of the insulating hood 16. Each rib 5 terminates in beads 18 protruding slightly beyond the edge of the insulating hood. Intermediate of these beads are concave recesses 19 from which moisture is readily discharged. I find that this arrangement facilitates the dripping of moisture which gathers in streams and flows through longitudinal channels 20 parallel with the wire, being discharged upon opposite sides of the wire and missing the cross arm 7. Auxiliary 10 wires 21 may be placed in these channels in cases of emergency or whenever desired, the weight of the wires retaining them in position. A wide channel 22 extends centrally of the insulating hood. A plate 23 of metal 15 is provided upon its under surface with hooks 24 directed toward each other and embedded within the body portion of the insulator hood, thus constituting anchorages which prevent the removal of the plate 23. This plate is provided with a substantially tubular portion 25 having a slot 26 extending 20 throughout the length thereof. Lugs 27, each of substantially semi-cylindrical form, are mounted integrally upon opposite sides 25 of the slot 26 and together constitute a divided stem, the two parts of which are separated by a slot 28. The inner ends of the substantially tubular member 25 are provided with threads 29, and the core 30 of a 25 tubular member 25 extends entirely through the latter and may be closed by substantially tubular clamps 31, threaded externally, as shown in Figs. 2 and 5. Each of these clamps is threaded, after the manner of 30 a screw, and is provided with a square head 32 and with a slot 33 extending entirely through the clamp. The clamp is preferably made with a tapered body, as indicated. 35 A screw cap 34 is provided with anchor- 40 ages 35, 36 and is embedded within a sheltering hood 37, in such manner that by turning this hood the screw cap 34 may be connected with or disconnected from the divided stem 27. By aid of this screw cap the 45 sheltering hood may be removed or replaced at will. The sheltering hood 37 is provided with indentations 38 for facilitating the flow of moisture from its surface at four distinct 50 points, as will be understood from Fig. 6. 55 The main wire or cable is shown at 39.

My invention is as follows: The body portion 15 and hood 16 being of insulating material are pressed up or cast preferably integrally, the metallic plate 23 and tubular member 25 being preferably embedded within the insulating material, as indicated in Fig. 2. The insulator pin 8 is next mounted upon the cross arm 7 or analogous support, and the body portion 13 is then screwed upon 65 the upper end of the insulator pin and turned

to such an extent that the plate 23 and its tubular portion 25 are parallel with the general direction in which the wire or cable 39 is to lie. The wire or cable may now be lifted into position or threaded through the tubular portion 25. The cored guards 31 may next be screwed into the ends of the tubular member 25. Preferably, however, the cored plugs 31 are placed approximately in their respective positions before the wire 39 is placed in position. The plugs are turned so that the slots 33 are uppermost and register with the slot 26, and the wire is raised and simply dropped into the slots. The guards 31 are then turned half a revolution (see Fig. 2) so that slots 33 are now downward whereby the wire is firmly and securely locked within the tubular slotted member 25 and cannot be dislodged or removed except by unscrewing the slotted clamping members. If desired, the sheltering hood 37 is next screwed into position. When this hood is employed it squeezes together the semi-cylindrical portions 27 thereby still further augmenting the locking action of the clamps; and effectually preventing any movement whatever of the locked parts.

It will be noted that owing to the general conformity of the upper surface of the protecting hood or umbrella, the moisture falling thereupon is prevented from flowing or dripping in excessive quantities upon the conductor, and is directed to flow and run or drip off at points some distance from the conductor.

I do not limit myself to the use of any particular materials from which to construct my insulator, but prefer to employ the insulating material well known in the art as "electrose" nor do I limit myself to the exact form nor to the details of any or all of the parts herein shown and described, nor to any particular combination of elements entering into the construction of my insulator, nor do I limit myself to employ in every instance a shield or umbrella for my insulator, nor to use in every instance a locking mechanism for the conductor, as it will be evident to those skilled in the art that changes in construction form and arrangement of the parts that may be resorted to without departing from the spirit or scope of my invention.

Having thus described my invention, I claim as new and desire to secure by Letters Patent:

1. An insulator comprising a body portion, a plate mounted thereupon and provided with a tubular portion for receiving a conductor, and clamps fitted into said tubular portion and provided with apertures through which a conductor may be threaded.

2. An insulator comprising a body portion, a metallic member mounted thereupon and provided with a slot, and plugs connected with said metallic member and provided

with slots adapted to register with said slot of said metallic member for the purpose of receiving a conductor.

3. An insulator comprising a body portion of insulating material, a metallic member connected therewith and provided with a central core and with a slot, and plugs screwed into the ends of said metallic member and provided with apertures registering with said core and further provided with slots adapted to register with said slot of said metallic member, said plugs being adapted to support a conductor and being revoluble for the purpose of bringing said slots of said plugs into registry with said slot of said metallic member.

4. An insulator member adapted to receive a conductor and having a greater length than breadth, said member being provided with longitudinally disposed barriers between the point that receives the conductor and the side edges so as to produce a striking distance at the sides approximately equal to the striking distance from the conductor to the base at the ends of the insulator.

5. An insulator, comprising a body portion of insulating material, a hollow slotted member having a portion embedded within said insulating material, said member being provided with a shank also having a slot, and a protecting hood mounted upon said shank.

6. An insulator comprising a hood of insulating material provided with ribs extending from edge to edge of said insulator hood, said ribs terminating in beads extending outwardly from said hood for facilitating the dripping of moisture.

7. An insulator comprising a hood of insulating material provided with ribs separated by channels, the ends of said ribs terminating in beads extending outwardly from said hood, the ends of said channels being concave for the purpose of facilitating the

dripping of moisture substantially as described.

8. An insulator comprising a body portion of insulating material, a metallic head mounted thereupon and provided with a portion having a slot for admitting a conductor, and a sheltering hood engaging said portion.

9. An insulator comprising a body portion of insulating material, a metallic member mounted thereupon and provided with a portion for supporting a conductor, and a sheltering hood mounted upon said portion of said metallic member.

10. An insulator, comprising a body portion provided with means for supporting a conductor, and a sheltering hood supported above said conductor, said sheltering hood being provided with a plurality of beads extending outwardly therefrom for facilitating the dripping of moisture therefrom in predetermined directions.

11. An insulator provided with a portion channeled to receive a conductor, said portion being threaded internally, and a clamping device threaded externally and fitting said channeled portion for the purpose of holding a line in position relatively thereto.

12. The combination of a member of substantially tubular form provided with ends, and with threads disposed internally of said ends, and further provided with a slot, and clamping members threaded externally and mating said ends of said first-mentioned member for the purpose of securing a conductor therein.

In testimony whereof I have signed my name to this specification in the presence of two subscribing witnesses.

LOUIS STEINBERGER.
